AND DAVID F. MEYER, COPARTNERS DOING BUSINESS AS LOUIS MEYERS & SON,
OF NEW YORK, N. Y.

SEMI-AUTOMATICALLY-CONTROLLED SEWING-MACHINE.

1,121,863.

Specification of Letters Patent. Patented Dec. 22, 1914.

Application filed September 5, 1913. Serial No. 788,216.

To all whom it may concern:

Be it known that I, GEORGE E. OATHOUT, a citizen of the United States, and resident of Watervliet, county of Albany, State of 5 New York, have invented certain new and useful Improvements in Semi-Automatically-Controlled Sewing-Machines, of which the following is a specification.

My invention relates to sewing machines 10 for making gloves and particularly to such machines when used for placing rows of ornamental stitching upon the backs of gloves as is usual in their manufacture.

In a pending application filed by me May 15 25, 1912, Serial Number 699,618 I have disclosed a mechanism which may be said to be completely automatic. The mechanism referred to is of such character that, once the machine is started in operation with the 20 glove back in place, there is formed a row of ornamental stitching of definite length, preceded and followed by a definite number of dead stitches which act to lock the ends of the rows of stitching so that they will 25 not unravel.

The mechanism of my prior application just referred to is, as has been said, of a completely automatic character and, while of great advantage in the manufacture of 30 a large number of gloves of the same size and type, is not so well adapted to the manufacture of successive small-lots of gloves of different sizes and type where it is desirable that the length of the row of stitches should 35 be different for the different kinds of gloves.

It is the object of my present invention to provide a mechanism which shall do exactly what my mechanism of the prior application, above referred to, will do, namely, 40 to place a row of ornamental stitches on the back of a glove, said row being preceded and followed by a definite number of locking stitches. In the present invention, however, I so arrange the mechanism that the 45 length of the row is not definitely determined by the character of the mechanism, but may be made anything that is desired. I call the mechanism semi-automatic as contrasted with the mechanism of the prior application, because the operation of making 50 a complete row of stitches with the preceding and following locking stitches, while a single and continuous operation, once the machine is started, regardless of the length

of the row, requires that the operator throw 55 a movable member in order to terminate the row of live stitches and to cause the mechanism to produce the determined number of dead terminal stitches and then stop.

The exact character of my invention will 60 be better understood by reference to the accompanying drawings, in which a preferred embodiment thereof is represented as applied to a sewing machine of the Wheeler & 65 Willcox type.

In the drawings, Figure 1 represents a front elevation of the machine; Fig. 2 represents a sectional plan along the line 2—2 of Fig. 1; Fig. 3 represents a sectional elevation along the irregular line 3—3 of Fig. 70 2; Figs. 4, 5, 6 and 7 represent respectively sectional elevations along the lines 4—4, 5—5, 6—6 and 7—7 of Fig. 2; Figs. 8 and 9 represent, respectively, partial sectional longitudinal elevations along the center line 75 and along the line 9—9 of Fig. 2; Fig. 10 represents an elevation taken from the right of Fig. 1, part of the structure being shown dotted; Fig. 11 represents an axial section 80 through the driving pulley and driving axis of the machine; and Fig. 12 represents a perspective of the yoke by means of which the feed is actuated.

Before describing my invention in detail, I will say that what I have done in applying 85 the same to the particular sewing machine here selected may be briefly stated as follows: I have arranged the driving pulley so as to have frictional engagement with the driving shaft sufficient to rotate the same 90 and operate the machine but have provided a lock which ordinarily engages said shaft so as to prevent its rotation, thus permitting the driving pulley to rotate independently.

I provide the operating shaft below the 95 base of the machine, which is connected with the driving shaft in the usual way, with a male clutch member keyed thereto and two slideable female clutch members, one on each side of the male member and connected together. With the slideable clutch members in one of their limiting positions, the feed is inoperative because below the bed plate of the machine, so that dead stitches 100 are produced through the operation of the operating shaft. As the operating shaft revolves in the production of the aforesaid dead stitches, an independent wheel or disk

- is actuated thereby so as, after a definite number of dead stitches have been made, to throw the slideable clutch members to their other limiting position, where they engage 5 a cam which throws the feed above the bed plate, and thus into action, so that live stitches are produced. The machine will go on producing these live stitches until the slideable clutch member is again thrown to 10 its first limiting position through the medium of a suitable member which projects above the bed plate, (or through an associated member adapted to be pressed by the knee of the operator) when the aforesaid in- 15 dependent disk is again thrown into gear and dead stitches formed until by the rotation of said disk a member is engaged which throws the lock which stops the driving shaft.
- 20 Referring now to the drawings, the driving shaft 1 has the driving pulley 2 mounted thereon and in frictional engagement therewith; in the embodiment shown a felt washer 3 is placed between the driving pulley and a collar 4 fixed upon the shaft. When the shaft is locked the pulley may be 25 readily rotated independently thereof, but when the shaft is free, the friction produced by the felt washer is sufficient to prevent 30 relative rotation of shaft and pulley so that the related mechanism is permitted to operate. The operating shaft 5 below the bed plate of the machine is connected with the driving shaft and actuates the stitching 35 mechanism in the usual way. Upon the operating shaft is keyed or otherwise firmly fixed, a male clutch member 6, comprising a ring having a projecting lug 7. On each side of the male clutch member is a female 40 clutch member comprising a short square-sectioned sleeve 8 loosely fitted to the shaft and having mounted slideably thereon, a ring 9 provided with a lug 10 projecting inwardly from the face thereof.
- 45 Upon the outer end of the left hand sleeve is fixed a disk 11 provided with a radially projecting pin 12 and having upon the outer face of the ring, a cam 13 embraced by a fork 15 which, when said cam rotates, oscil- 50 lates a shaft 16' so as to alternately throw the feed 16 above and below the bed plate in the usual manner. At the outer end of the right hand sleeve 8 is fixed a disk 17 having a radially projecting pin 18 and 55 upon its face an interrupted ring 19 and pin 20.
- An intermittent motion disk 21, having 60 equally spaced radial slots 21' separating peripheral concave segments or teeth 21², is pivotally mounted upon the frame of the machine so that, as the ring 19 revolves, the pin 20 will engage one of the slots 21' once for each revolution of the ring and move the disk 21 through an angle represented 65 by one tooth, the concave portion of each

tooth engaging the peripheral surface of ring 19 so as to hold it immovable, until the pin 20 again comes around. This particular part of the mechanism will be recognized as the well known "Geneva stop."

A pin 22 projecting from the outer face of the disk 21 will, when this disk comes around into a suitable position, engage a member 23 fixed upon a shaft 24 carrying a hooked lever arm 25 so as to throw said 75 arm inwardly toward the driving shaft in position to engage the stop 26 fixed to said shaft. Another pin 27, also projecting from disk 21 but nearer the axis thereof, will when it comes around, engage a member 28 80 fixed to a shaft 29 which carries a lever arm 30 lying just below the bed plate; this arm has fixed upon its outer end, a pin 31 which projects through and above said bed plate, and is topped with a button 31'. Fixed 85 upon shaft 29 is a short outwardly projecting lever arm provided with a link attached to two shifting members 32 provided with pins which engage respectively the annular rings 33 of the female clutch 90 members. The two shifting members must, therefore, move as one.

Upon the outside of each shifting member and linked thereto so as to move therewith is a locking link 34 provided with a notch 35 upon its outer face; according as the linked shifting members are in one limiting position or the other will pin 12 or pin 18, as the case may be, be engaged by one of these notches and in this way the particular clutch 160 member sleeve to which the pin belongs be prevented from rotating.

A pin 35 held slideably in a bracket 36 pivoted to the frame of the machine is itself pivoted to the end of lever arm 105 30; a spring 37 exerts a constant pressure upon the pin in the direction of said lever arm and thereby tends to hold said arm either in its upper or lower limiting position. Lever arm 30, through a right angled extension thereof, connects with a bell crank lever provided with a knee pad 38. At the right of the machine in position to be engaged by the right knee of the operator is a second knee pad 39 fixed upon one 115 arm of a bell crank lever 40, the other arm of which carries a flat disk 41 upon which rests the usual lifting rod 42 through which the presser foot may be raised. A disk 43 is fixed to lifting rod 42 in such a position 120 that, as said rod is raised, the disk engages with a short lever arm 44 fixed upon the shaft 24, which carries lever arm 25.

The operation of my improved machine is as follows: The machine being at rest with 125 stop 26 engaged by the hooked lever arm 25 (Fig. 10) and with the sliding clutch elements in their left hand limiting position (Fig. 9), the knee pad 39 is pressed to the right, thus raising the presser foot 42' so 130

as to enable the glove back to be slipped thereunder, and simultaneously disengaging arm 25 from stop 26. The power is then thrown on and the driving pulley 2, by reason of its frictional engagement with the driving shaft, causes the operating shaft 5 to be rotated. The sliding clutch elements being in their left hand position the pin 12 of disk 11 is engaged by its locking link 34 and the cam 13 formed upon said disk is held against rotation in such position as to maintain the feed 16' below the level of the bed plate. The right hand female clutch member is engaged with the male clutch member 6 so that the disk 17 with its interrupted ring 19 rotates with the operating shaft. At each revolution of this shaft, as has been explained before, a slot of disk 21 is engaged by the pin 20 so as to advance the 20 disk through the angle represented by one tooth. As shown, there are 8 slots in all in disk 21 and after 4 of these slots have been engaged and the disk rotated correspondingly, the pin 27 which projects from the 25 face of disk 21 will engage the member 28 so as to rotate shaft 29 and shift the slidable clutch member from its left hand to its right hand limiting position, while at the same time raising the lever arm 30. This will 30 cause the left hand sleeve, through its lug 10, to be engaged by lug 7 of the male clutch member and, consequently, will cause rotation of cam 18, thereby alternately lifting the feed 42' above and below the level of the 35 bed plate. A row of live stitches will now be formed in the usual manner and this row will continue until the lever 30 is thrown down, either by pressing with the knee on the left hand knee pad 38 or, with the hand, 40 on the button 31', so as to again throw the slidable clutch member to the left. This again locks disk 11 and the cam fixed thereto, with the feed below the level of the bed plate and compels the machine to make only 45 dead stitches. At the same time the right hand disk 17 again begins to revolve the disk 21, step by step as before, until 4 slots 21' have been again engaged and consequently 4 dead stitches formed. Pin 22 will 50 thereby have been brought around in position to engage member 23, whereby hooked lever arm 25 will be thrown inwardly toward the driving shaft into engagement with the stop 26. This stops the mechanism 55 and power may then be thrown off and the completed glove back withdrawn.

In order that the operating mechanism may not receive too severe a jar by reason of the sudden stoppage of operating shaft 1, I 60 prefer to make the collar 4 as indicated in Figs. 1 and 11. Here the collar is divided centrally and transversely to its axis, the

two faced portions being formed with interlocking ratchet teeth and united together by a coiled spring 4'. The lug 26 is attached to that half of the ring nearest the driving pulley which half ring is loose upon the driving shaft. The left half ring is keyed or otherwise tightly fixed upon said shaft. As a consequence when the lug 26 is suddenly 65 caught by the lever arm 25, the driving shaft with the left hand ring will continue to rotate through a small angle against the resiliency of the spring which is tightened within said angle and until the teeth of the 70 opposing faces come in contact with one another, these teeth being formed so that there is a small amount of play between the end surfaces of opposing teeth.

Numerous changes in details of construction and exact arrangement of parts may be made without departing from the spirit of my invention, the particular form illustrated and described being merely the one in which I have found it most convenient to embody 80 the invention.

Having described my invention, I claim:

1. In a sewing machine, means for making a series of dead stitches, automatic means for changing from dead to running stitches, means for manually changing from running to dead stitches without stopping the machine, and automatic means for stopping the machine after a definite number of dead 90 stitches have been made.

2. In a sewing machine, means for making a definite number of dead stitches, automatic means for changing from dead to running stitches, means for manually changing from running to dead stitches without stopping the machine, and automatic means for stopping the machine after a definite number of dead 100 stitches have been made.

3. In a sewing machine, in combination with the driving shaft, a driving pulley 105 frictionally engaged with said shaft, a lock for said driving shaft, means for simultaneously releasing said lock and temporarily raising the presser foot, means for making a definite number of dead stitches, means for automatically changing from dead to running stitches, manually operated means for again changing to dead stitches, and automatic means for locking the driving shaft after a definite number of dead 110 stitches have been made.

In testimony whereof, I have hereunto set my hand in the presence of two subscribing witnesses.

GEORGE E. OATHOUT.
